UNITED STATES PATENT OFFICE.

JOSEPH STRYKUL, OF SOUTH BEND, INDIANA.

WASHING-MACHINE.

1,367,286.

Specification of Letters Patent.

Patented Feb. 1, 1921.

Application filed June 11, 1920. Serial No. 388,135.

To all whom it may concern:

Be it known that I, JOSEPH STRYKUL, a citizen of the United States of America, residing at South Bend, in the county of St. Joseph and State of Indiana, have invented certain new and useful Improvements in Washing-Machines, of which the following is a specification.

The present invention relates to certain new and useful improvements in washing machines and particularly to that type that is driven by an electric motor or other power device and embodying a rotating clothes containing cylinder.

15 A further object of the invention is to provide in a clothes washing machine, a motor driven clothes containing drum within a casing with a burner attachment arranged adjacent the bottom wall of the casing for 20 heating the fluid contents.

A still further object of the invention resides in the provision of a motor driven washing machine with a novel form of clutch device between the motor and clothes 25 containing cylinder that is operable to permit the removal of the cylinder from the supporting casing.

With the above and other objects in view, the present invention consists in the novel 30 form, combination and arrangement of parts hereinafter more fully described and shown in the accompanying drawings, wherein like reference characters indicate similar parts throughout the several views.

35 In the drawings,

Figure 1 is a vertical longitudinal sectional view of a washing machine constructed in accordance with the present invention showing the burner attachment beneath the casing,

Fig. 2 is a horizontal longitudinal sectional view of the device,

Fig. 3 is an end elevational view,

40 Fig. 4 is a vertical transverse sectional view,

Fig. 5 is a detail sectional view showing the driving gear and clutch mechanism for rotating the inner cylinder,

Fig. 6 is a detail sectional view similar 45 to Fig. 5, and

Fig. 7 is a cross sectional view taken on line VII—VII of Fig. 5 showing the clutch shifting lever.

Referring more in detail to the accompanying drawings, there is illustrated a washing machine embodying a casing 1,

preferably rectangular in cross section as shown in Fig. 4 and having a hinged cover 2, the receptacle 1 being mounted upon supporting legs 3 at each corner thereof. The 60 casing 1 is adapted to contain water or other fluid and is heated by the gas burner 4 arranged within the chamber provided by the casing wall 5 and supplied through a valve controlled gas pipe 6, the burner being ignited by a match or other torch through the opening 7 in the wall 5.

A rotatable clothes containing drum is journaled within the casing 1 and is driven by a motor 8 controlled by the switch 9 and 70 mounted upon the bracket 10 carried by one end wall of the casing 1. A stub shaft 11 is journaled in the lower end of the casing 1 as shown in Fig. 1 and carries a relatively large sprocket wheel 12 over which a 75 sprocket chain 13 passes, the opposite looped end of the sprocket chain 13 passing over the sprocket wheel 14 carried by the shaft of the motor 8. A pinion 15 is fixed to the shaft 11 inwardly of the sprocket wheel 12 and is in 80 constant mesh with the relatively large gear wheel 16, the mounting of which is more clearly shown in Figs. 5 to 7.

The end wall of the casing 1 is provided with an outwardly directed annular flange 85 17 that rotatably receives the tubular hub 18 of the gear 16, the periphery of the hub 18 being provided with an annular groove for freely receiving the inner end of the retaining screw 19. A stub axle 20 is journaled 90 within an opening in the wall of the casing 1 inwardly of the flange 17 and is keyed to the gear 16 as at 21, the gear 16 and axle 21 revolving in unison within the casing flange 17. The inner end of the stub shaft 20 carries a block 22 having a vertical slot 23 therein with lugs 24 depending from the block 22 beneath the slot. A reversed L-shaped lever embodying a vertical leg 25 has the lower end thereof pivoted within the 100 lugs 24 and extending upwardly as at 26 into the slot 23 provided in the axle block 22. A spring 27 is arranged between the rear wall of the slot 23 and the end 26 of the lever and is in engagement with a clutch block 28 105 for normally forcing the same outwardly of the block slot 23.

The clothes containing drum includes a cylinder 29 provided with perforations over the cylindrical surface thereof, and is rotatably mounted within the casing 1. The end wall of the casing 1 opposite the motor

mechanism is provided with a block bearing 31 having a vertical socket 32 therein for receiving the bearing pin 33 upon the adjacent end of the cylinder 29. The opposite 5 end of the cylinder is shown in detail in Figs. 5 and 6 and is provided with an axle opening 34 into which the clutch block 28 is forcibly projected by the spring 27 for engagement with the clutch face formed upon 10 the disk 35 extending over the opening 34.

In the operation of the device, assuming that water or other cleaning fluid is contained within the receptacle 1 and the articles to be cleaned are within the cylinder 29, 15 the motor 8 is put into operation and by the chain and sprocket mechanism and meshing gears, rotary motion is indicated to the cylinder 29. When it is desired to remove the cylinder from the casing 1, the vertical leg 20 of the lever 25 is operated to move upon the pivot 24 to shift the inner end 26 thereof carrying the clutch block 28 from engagement with the clutch disk 35, at which time the cylinder may be moved vertically 25 through the open upper end of the casing. The fluid within the casing is heated by the burner 4 and the casing is drained by means of the outlet spout 36 shown in Fig. 1. The clothes cylinder 29 is replaced in the casing 30 1 by positioning the pin 33 in the socket 32 and by withdrawing the clutch block 28 until the same registers with the opening 34 in the end wall of the cylinder 29, at which time the spring 27 will force the clutch 35 block into the opening and into engagement with the clutch face of the disk 35.

While there is herein shown and described

the preferred embodiment of the invention, it is nevertheless to be understood that minor changes may be made therein without departing from the spirit and scope of the invention as claimed.

What is claimed as new is:

1. A washing machine comprising a casing, bearing blocks mounted in the end walls 45 of the casing, a rotatable cylinder supported on said bearing blocks, one of said blocks being rotatable in the casing wall, means for rotating said block, coöperating axially aligned clutch members carried by the rotatable bearing and cylinder with the cylinder supported on the clutch member carried by the bearing, and an arm projecting from the clutch member carried by the rotatable bearing to disengage the same from the axial 55 clutch member on the rotating cylinder to permit removal of the cylinder.

2. A washing machine of the character described comprising a casing, bearing blocks carried by the end walls of the casing, a cylinder rotatably supported in said bearing blocks, one of said bearing blocks being fixed to the casing end and the other of said bearing blocks being rotatably mounted and extending at opposite sides of the carrying 60 end wall and having a transverse opening therein, a gear fixed to the outer projecting end thereof, an angle lever pivotally mounted on said block and extending into the transverse opening, and coöperating clutch 65 devices carried by the lever within the block opening and the end of the cylinder.

In testimony whereof I affix my signature.
JOSEPH STRYKUL.
